US0D1009733S

(12) **United States Design Patent** (10) **Patent No.:** **US D1,009,733 S**
(45) **Date of Patent:** **** Jan. 2, 2024**

(54) **FENDER**

(71) Applicants: **Nicholas A. Malachowski**, Bloomfield Hills, MI (US); **Eugenio Sellaro-Neto**, Detroit, MI (US); **Matthew W. Dunford**, Clawson, MI (US); **Alexander Tannen**, Detroit, MI (US); **Chris Piscitelli**, West Bloomfield, MI (US); **Jeffrey C. Gale**, Rochester, MI (US); **Mark D. Hall**, Rochester Hills, MI (US); **Mark T. Allen**, Oxford, MI (US)

(72) Inventors: **Nicholas A. Malachowski**, Bloomfield Hills, MI (US); **Eugenio Sellaro-Neto**, Detroit, MI (US); **Matthew W. Dunford**, Clawson, MI (US); **Alexander Tannen**, Detroit, MI (US); **Chris Piscitelli**, West Bloomfield, MI (US); **Jeffrey C. Gale**, Rochester, MI (US); **Mark D. Hall**, Rochester Hills, MI (US); **Mark T. Allen**, Oxford, MI (US)

(73) Assignee: **FCA US LLC**, Auburn Hills, MI (US)

(**) Term: **15 Years**

(21) Appl. No.: **29/840,334**

(22) Filed: **May 27, 2022**
